UNITED STATES PATENT OFFICE.

JOSEPH J. SLEEPER, OF MOORES, PENNSYLVANIA.

PUMP FOR SUCTION-CLEANERS.

1,093,014.

Specification of Letters Patent. Patented Apr. 14, 1914.

Original application filed January 9, 1912, Serial No. 670,239. Divided and this application filed April 16, 1912. Serial No. 691,235.

To all whom it may concern:

Be it known that I, JOSEPH J. SLEEPER, a citizen of the United States, residing at Moores, in the county of Delaware and State 5 of Pennsylvania, have invented certain new and useful Improvements in Pumps for Suction-Cleaners, of which the following is a specification.

My invention relates to improvements in 10 pumps for suction cleaners, the object of the invention being to provide a device of this character with improved suction creating means operated by the weight of the person on a pivoted platform, and comprising two 15 diaphragm pumps of improved construction, together with an improved arrangement of valves, whereby a strong suction is had.

A further object is to provide an improved 20 suction cleaner having a central dust collector with which at both sides, diaphragm pumps have valved communication, whereby a continuous suction is had from both sides of the dust collector, insuring a continuous 25 operation with a uniform suction.

This is a division of my application for 30 patent on suction cleaners, filed January 9, 1912, and given Serial No. 670,239.

With these and other objects in view, the 35 invention consists in certain novel features of construction and combinations and arrangements of parts, as will be more fully hereinafter described and pointed out in the 40 claims.

In the accompanying drawings: Figure 1, 45 is a view in longitudinal section illustrating my improvements. Fig. 2, is a view in horizontal section on the line 2—2 of Fig. 1. Fig. 3, is a view in section on an enlarged scale on the line 3—3 of Fig. 1. Fig. 4, is a 50 view in section on the line 4—4 of Fig. 3. Fig. 5, is a bottom plan view of my improved suction nozzle. Fig. 6, is a view in transverse section through the center of the nozzle showing the pipe in elevation. Fig. 7, is a 55 view in vertical section on an enlarged scale through one of the packing rings or collars. Fig. 8, is a view in section on the line 8—8 of Fig. 7.

1, represents the dust collecting chamber, 60 which is preferably of rectangular form as illustrated, having its ends extending above the top, and converging to a point whereby a fulcrum is formed for a platform 2.

To hold the platform in position on the 65 fulcrum, links 3 pivotally connect brackets

4 on the bottom of the platform with the ends of the dust collecting chamber. The said platform, near its respective ends on its under face, is provided with brackets 5, which are pivotally connected to rods 6 of 60 diaphragm pumps 7. The diaphragm pumps are both alike, and each comprises a casing consisting of two half sections both of general truncated conical form, with their larger ends secured together as clearly shown 65 in Fig. 1. At the juncture of these sections, flanges 8 are formed, and are secured by bolts 9 and nuts 10 confining the edges of leather sheets 11. These leather sheets, at their center, are provided at opposite sides 70 with plates 12, secured by bolts 13, and nuts 14, and to the center of these plates 12, the rods 6 above referred to are secured, and project through openings 15 in the top of the pump casings. As these rods 6 are 75 moved laterally, due to the action of the platform 2, the openings 15 are appreciably larger than the rods and collars 16, are secured on the rods, and normally close the 80 openings. These collars are made with internal grooves in which packing 21 is located, and is pressed against the rod by means of set screws 17, having segments 18 at their inner ends.

On top of each pump casing, around the 85 opening 15, a sheet of leather or felt 19 is secured, and against these sheets 19, the collars are snugly held by means of bow springs 20 secured at one end to the top of the pump casing, and at their free ends bearing down 90 on the collars. Each pump casing is connected to the side of the dust collector 1 by means of two pipe sections 22, the upper pipe section communicating with the pumps above the diaphragm (consisting of the 95 leather sheet 11 and the plates 12) and the other pipe section with the pump casing below the diaphragm. These pipe sections 22 are divided by valve mounts 23. Each valve mount comprises a sheet of metal bent into 100 general angular form, so that when it is secured in the pipe section, it will form a V-shape partition, dividing each pipe section into an inlet chamber 24, and an outlet chamber 25, the former communicating with the 105 dust collector, and the latter with the outside air through the medium of perforations 26 in the top of pipe section 22, said perforations normally closed by flap valves 27.

The valve mount in both members of the 110

V-shaped partition which it forms, is provided with perforations the passage through which being normally closed by spring held flexible valves 28 and 29 respectively, the 5 former constituting the valve controlling the passage to the pump, and the latter the passage from the pump. The valves 27 comprise strips of leather secured by metal strips 30, and having weights 31 thereon to hold them in closed position. The valves 10 28 and 29 consist of a strip of leather, the ends of which are inclosed in metal binding strips 32. These binding strips consist of a sheet of metal folded longitudinally and 15 clamped or otherwise secured to the ends of the leather, and said metal strips have perforations 33 in their ends through which the ends of springs 34 project. These springs 34 are connected between their ends to rivets 20 35 fixed in the partition, and said springs exert a pull longitudinally on the leather to hold it flat and in close engagement with the partition insuring a perfect closure. The springs, however, permit the free egress of 25 air yet quickly close the valve. A flexible tube 36 connects the suction chamber 1 with a tubular handle 37, and the latter is provided at its free end with a suction nozzle 38. The nozzle 38 is of general rectangular form having a flange 39 at its edge on its lower face forming a box-like compartment providing an extended surface area, the lower face of 30 said nozzle tapering to the opening 40 which communicates with the tubular handle. This 35 tubular handle has a curved end as shown at 41, and is pivotally connected by pins 42 to angle brackets 43 secured to the upper face of the nozzle, and between the lower end of the tubular handle and the nozzle, 40 washers 44 of rubber or other elastic material are interposed. These flexible washers and the pivotal connection between the handle and the nozzle, permit the nozzle a certain amount of movement relative to the 45 handle, so that the nozzle may cling closely to the carpet or floor, and allow the handle a certain amount of angular movement relative thereto. This renders the operation of moving the nozzle about the floor much 50 easier than is the case where the nozzle and handle have a rigid connection, because the nozzle must be maintained in proper position on the floor, and hence the angle of a rigid handle cannot change, but the movement must be compensated for by an awkward 55 movement of the arm of the user.

Various slight changes might be made in the general form and arrangement of parts described without departing from my invention, and hence I do not limit myself to the 60 precise details set forth, but consider myself at liberty to make such changes and alterations as fairly fall within the spirit and scope of the appended claims.

Having thus described my invention, what 65 I claim as new and desire to secure by Letters Patent is:

1. A suction creating pump comprising a casing, a diaphragm in the casing, pipes communicating with the casing above and 70 below the diaphragm, approximately V-shaped partitions in said pipes having perforations therein dividing said pipes into upper outlet chambers, lower inlet chambers, and intermediate chambers communicating 75 with the casing, and valves normally closing said perforations and moved by the passage of air caused by the operation of the diaphragm, substantially as described.

2. A suction creating pump comprising a 80 casing, a diaphragm in the casing, pipes communicating with the casing above and below the diaphragm, approximately V-shaped partitions in said pipes having perforations therein, valves normally closing 85 said perforations and moved by the passage of air caused by the operation of the diaphragm, said pipes having perforations in their upper faces, and flap valves secured to said pipes and normally closing the last 90 mentioned perforations, substantially as described.

3. The combination with a suction chamber, of diaphragm pumps at opposite sides of said chamber, pipes connecting both of 95 said pumps with the chamber, each pump having two pipes, one located above and the other below the diaphragms therein, V-shaped partitions in all of said pipes having perforations therein, the upper faces of all 100 of said pipes having perforations therein above the partitions, and valves normally closing said perforations and moved by the passage of air therethrough, substantially as described.

In testimony whereof I have signed my name to this specification in the presence of two subscribing witnesses.

JOSEPH J. SLEEPER.
